UNITED STATES PATENT OFFICE.

LOUIS WIMMER, OF ELIZABETH, NEW JERSEY, ASSIGNOR OF ONE-HALF TO
ELIAS D. SMITH, OF SAME PLACE.

ORE CRUSHER AND PULVERIZER.

SPECIFICATION forming part of Letters Patent No. 380,006, dated March 27, 1888.

Application filed January 27, 1887. Serial No. 225,729. (No model.)

To all whom it may concern:

Be it known that I, LOUIS WIMMER, a citizen of the United States, and a resident of Elizabeth, in the county of Union and State of New Jersey, have invented certain new and useful Improvements in Ore Crushers and Pulverizers, of which the following is a specification.

The present invention relates to a machine for crushing and pulverizing ores, stones, paints, artificial cements, sugar, and similar massive pieces of material.

The machine is so constructed that when the ore is first put into the hopper the former is first crushed into smaller pieces by the rotation of a crushing-cylinder. The ore then passes between disks, which cause it to be crushed finer and finer, until it issues from the machine in the form of powder, comparatively fine.

Figure 1 is a central vertical section, partly in elevation, and Fig. 2 is a side view, of the face of one of the stationary disks; and Fig. 3 is a detail sectional view of the grinding-disks, showing that the holes in the casing and in the grinding-disks *f* are made considerably larger, so that the ore can pass from the casing *b* approximately as fast as it enters said casing.

The machine consists of the combination of a conical receiver, hopper, or mouth-piece, *a*; a casing, *b*, having an opening in which fits said hopper; a crushing-wheel, *c*, consisting of two truncated cones having their opposite ends common, and each one having a projection, *d*, running along one of the elements of the cone; a ring, *A*, surrounding those ends of the cone which are common to each other, to divide the entering ore; a shaft, *e*, upon which is fastened rigidly said wheel; a hole in each end of said casing, through which passes the said shaft, the holes being larger than the shaft; disks *f*, secured to the ends of said casing, and provided with holes which are concentric with the holes in the end of the casing, and with an inner set, *g*, of coarser teeth and an outer concentric set, *h*, of finer teeth, and other disks, *f'*, facing the first disks and having teeth of a similar nature to those of the first-named disks, but not provided with a hole other than that for the passage of the shaft *e*.

The machine consists, further, of long keys or projections *i* upon the shaft, the shaft and

these projections passing loosely through the hubs *j*, secured to the frames *k* and the disks *f'*, frames *k* having hubs or supporting parts *l*, through which passes loosely the shaft, and bolts *m*, carried by said frames and supporting helical springs *n*, which press both upon said frames and upon the disks *f'*, the said bolts passing through the disks *f'*. The casing *b* in cross-section is cylindrical, the axis of the cylinder being coincident with that of the main shaft *e*. To the casing *b* are also secured the hollow frames *o*, which serve as supports for large rotating nuts *p*, which screw upon the parts *o*, and which turn independently of the shaft. The nuts *p* press by means of the projections *q* upon the frames *k*, and are provided with crank-handles *r*. The nuts *p* are made rotatable upon the parts *o* by means of screw-threads *s*. In the lower portion of the frames *o* are exits *t*. The foundation *u* supports the casing, and it has two arms, *v*, which serve as bearings for the shaft. A fly-wheel, *w*, (partially shown,) is located upon the other end of the shaft. The ends of the casing *b*, disks *f*, and the hollow frame *o* are secured together rigidly by means of suitable bolts passing through the little holes shown in Fig. 2. The disks *f'* are loose upon the shaft, but are rotatable with the shaft, because of the ridge or projection *i* passing through its hub. The bolts *m* pass through suitable holes (not shown) in disks *f'*, while the springs *n* press against the disks *f'* and against the frame *k*.

The object of the annular projection between the two parts of the conical crusher *c* is to cause the ore to be divided into two parts, so that a portion of the ore will pass to the right and the rest to the left.

The object of the pulley *x* is that, a propelling-belt being placed upon it, the machine may be operated.

By means of the two independent sets of pulverizing-disks at the ends of the casing *b*, it is evident that two grades of fineness may be obtained simultaneously from the same machine by properly manipulating the handles or cranks *r*.

When the ore or similar material is placed in the mouth-piece, and when the machine is operated from the driving-pulley, the projections *d* cause it to be broken into smaller

pieces, which are carried to other portions of the casings *b*. It is further broken by crushing against other pieces of ore and against other portions of the casing *b*, and it gradually fills the latter until it issues between the said coarser teeth and then through the said finer teeth, and finally through the exits *t*. The springs *n* yield when exceptionally large or hard pieces come between the disks, there-
5 by preventing injury to the machine.

By turning the cranks *r* in one way or another the machine may be made to grind coarser or finer, as desired. The end holes of the casings and the holes in the disks *f* may
15 be larger, as shown in Fig. 3, and other proportions of the machine may be varied without departing from the spirit of the invention.

I lay no claim to the character of the inner surface of the casing *b*. Whether it is rough
20 or smooth, more or less breaking of material

will occur, not only by the passage of the projection over the mouth of the hopper, but also after the ore or similar material has completely entered the casing, on account of the impossibility of doing away with friction.

25

I claim as my invention—

In a crusher or pulverizer, the combination of a suitable casing provided with a hopper, a crushing-wheel, and two independent pairs of pulverizing-disks, located at opposite ends of 30 the casing and receiving the material therefrom, substantially as described.

In testimony that I claim the foregoing as my invention I have signed my name, in presence of two witnesses, this 12th day of Jan- 35
uary, 1887.

LOUIS WIMMER.
